UNITED STATES PATENT OFFICE.

JACOB KRABILL, OF MANSFIELD, OHIO.

ORE-SEPARATOR.

No. 926,577.

Specification of Letters Patent.

Patented June 29, 1909.

Application filed April 17, 1908. Serial No. 427,724.

To all whom it may concern:

Be it known that I, JACOB KRABILL, a citizen of the United States, residing at Mansfield, in the county of Richland and State of Ohio, have invented new and useful Improvements in Ore-Separators, of which the following is a specification.

This invention relates to an improved machine adapted to operate upon dry pulverized material, such as pulverized ore, to separate the lighter from the heavier constituents thereof, and the object of the invention is to provide a device of this character which is simple in construction, comparatively cheap in manufacture, and the parts of which are so arranged as to be readily adjustable to regulate the feed as well as to control the separate elements in their action upon the ore to be separated.

With these and other objects in view the invention resides in the novel construction of elements and their arrangement in operative combination, hereinafter fully described and claimed.

In the accompanying drawings, Figure 1 is a side elevation of an apparatus constructed in accordance with the present invention. Fig. 2 is a transverse sectional view upon the line 2—2 of Fig. 1. Fig. 3 is a longitudinal sectional view of the rotary drum, illustrating its connection with the stationary drum.

In the accompanying drawings the numeral 1 designates the frame of the device. This frame 1 has one of its ends provided with a settling box 2 having a pipe connection 3 with a suction fan 4. This pipe 3 is provided with a suitable sliding valve 5 having a longitudinally extending stem 6 mounted in suitable bearings and provided with an operating handle 7 positioned adjacent the opposite end of the frame. The deflector box 2 is provided with a spout 8 connected with an inclined stationary separating cylinder 9. This cylinder 9 is provided at its free end with a collar 10 having a strap 11 by which it is supported from the longitudinal members of the frame 1. The collar 10 and the drum 9 are each provided with a suitable aligning opening adapted for the reception of

a spout 12 connected with a feed hopper 13. The spout 12 is provided with a rotary drum 14 and is also provided with an inclined plate 15, whereby the material within the hopper 13 is fed directly upon the upper portion of the drum 14. The spout 12 is also provided with a hinged valve 16 having its lower edge contacting the periphery of the drum 14. The valve 16 is provided with a suitable valve stem 17 mounted in suitable bearings and having its operating handle 18 positioned adjacent the handle 7 of the valve 5. By this construction it will be noted that the material from the hopper 13 directed upon the drum 14 by the inclined plate 15 may be regulated in its flow through the spout to the separating cylinders by the valve 16. The drum 14 is provided with a suitable shaft extending upon the side of the spout 12 and provided with a suitable pulley 19 adapted for engagement with an endless belt 17', and this belt 17' is adapted to engage a similar pulley 18 connected with a suitable motor or other operating device.

The collar 10 is provided with a flange 19, and this flange 19 is provided with a plurality of rollers 20. The numeral 21 designates the rotary drum or cylinder of the device. This drum 21 is adapted to be positioned within the collar 10 adjacent the end 80 of the cylinder 9, and is contacted by the rollers 20 whereby friction caused by the rotation of the drum is minimized. The drum 21 has its opposite end closed and is provided with a plurality of cut away portions or openings 22 extending in spaced relation with each other around the annular circumference of the drum. These openings 22 are positioned directly above a spout 23 connected with a suitable receiving vessel 24.

An agitator shaft 25 extends axially through the cylinders 9 and 21, passing through the caps at both ends thereof. The shaft 25 is provided with agitator brushes 26, and these brushes are positioned a suitable distance away from the interior surfaces of the cylinders 9 and 21 whereby the brushes being held free from contact, all rubbing or grinding of the ore against the drums is obviated. The upper end of the shaft 25 is con-

nected with the motive power which rotates the pulley 18 and the roller 14, while the lower end of the shaft 25 is extended through the closure of the cylinder 21, and through a suitable bracket 27 provided upon one of the vertical members of the frame. This end of the shaft 25 is provided with a conical recess adapted for engagement with a bearing stud 28. This stud 28 is provided with threads 10 and is adapted to work in a threaded aperture provided upon a bracket 27. The end of the shaft 25 within the bracket 27 is provided with a suitable friction wheel 28, which contacts with a larger friction wheel 29, also 15 mounted in bearings within the bracket 27. The shaft of the wheel 29 extending beyond the bracket 27 is provided with a smaller wheel 30 adapted to contact with an annular surface 31 provided by the closure for the rotary cylinder 21. By this construction it will be noted that as the agitator brushes 26 are rotated the shaft 25 imparts motion to the rotary cylinder 21 through the medium of the friction wheels 28, 29 and 30 contacting 20 with the annular surface 31 of the closure of the cylinder, and that by this arrangement the ore deposited within the cylinders is thoroughly agitated.

In the settling box 2 between the pipes 30 and 8 is a deflector plate 32. This plate 32 is hingedly secured between the sides of the box 2 and is provided with a regulating handle 33, by which the plate may be swung toward the pipe 8 of the cylinder or toward 35 the pipe 3 of the suction fan 4 to regulate the flow of air through the cylinders to the settling box. By this arrangement it will be seen that the box 2 is provided with a partition which separates that part of the box into 40 which the air flows from that part of the box from which it flows. The air carrying the lighter particles must therefore dive beneath this partition in passing from the inlet to the outlet of the box. As a matter of fact the 45 practical result of the construction is that all of the pulverized particles will collect upon the inclined bottom 34 of the box 2. The box is provided with a pivoted door 35, and when a sufficient quantity of the material 50 is collected upon the bottom 34, the door 35 will automatically open and allow the particles to slide out of the box. It will be noted that the flow of air through the box 2 is readily regulated by the valve 5 connected 55 with the outlet pipe 3.

Although the particles fed to the cylinders may be of the same size, the heavier particles may be friable and so become broken up as they are tossed around within the cylinders. 60 Such broken particles becoming smaller become also lighter and are carried away by the air current into the settling box. It is of course understood that the heaviest particles will fall within the rotary drum 21 and

through the openings 22 into the receptacle 24, the lighter particles being carried through the cylinder 9 through the pipe 8 to the settling box 2 by the air from the suction fan 4 as previously described. By constructing the separator with the rotary drum 21, it will 70 be noted that the brushes 26 may be positioned a suitable distance away from the cylinders, and that by this construction the grinding or rubbing of the ore against the drums is entirely obviated, thus prolonging 75 the life of the brushes and the cylinders.

Having thus fully described the invention what is claimed as new is:

1. The combination with a stationary and a rotary cylinder, the rotary cylinder having 80 a closed end and provided with a plurality of openings adjacent said end, a feed box positioned above one of the cylinders, the stationary cylinder having an outlet communicating with a settling box, a suction fan connected with the settling box, a shaft extending axially through the cylinders, rush members connected with said shaft and positioned a distance away from the cylinders, and means for rotating the shaft. 90

2. The combination with a frame provided with a settling box of a stationary and a movable cylinder, a collar upon one of the cylinders, rollers carried by said collar contacting the movable cylinder, a connection 95 between the immovable cylinder and the settling box, a suction fan for the settling box, a feed hopper communicating with the stationary cylinder, a valved door within the hopper, means for regulating the opening 100 provided by the door, the movable cylinder having one of its ends closed and provided with a plurality of openings adjacent the said closed end, a shaft within the cylinders, brushes upon the shaft positioned out of 105 contact with the cylinders, and means for revolving the movable cylinder.

3. In a device of the character described, a frame, a suction fan upon the frame, a settling box having an inclined bottom connected with the fan, a slide valve for the connection, an operating rod for the valve, a deflector plate within the settling box, a valve outlet for the box, a tube connected with the box, an inclined cylinder connected 110 with the tube, a collar upon the cylinder, a flange upon the collar having rollers, a feed box connected with the collar and the cylinder, means within the cylinder for regulating the flow of material from the feed box to the cylinder, a second cylinder within the collar of the first cylinder and engaging the rollers, a series of openings provided by the second cylinder near the closed end thereof, an agitator shaft extending through the cylinders, 115 an agitator brushes upon the shaft spaced from the cylinders, a bracket provided by the frame for the lower portion of the agitator 120 125

shaft, the end of the agitator shaft being provided with a cone-shaped recess, a threaded pin upon the bracket engaging the cone-shaped recess, a friction wheel upon the 5 shaft within the bracket contacting a friction wheel upon the bracket, a smaller friction wheel engaging the annular portion of the closure of the lower cylinder, means for

revolving the agitator shaft, and means for operating the suction fan.

In testimony whereof I affix my signature ¹⁰ in presence of two witnesses.

JACOB KRABILL.
